Inventor

Edward R. Crockett.

By *Mason Farnie Lawrence*,
Attorney

UNITED STATES PATENT OFFICE.

EDWARD R. CROCKETT, OF NEW YORK, N. Y.

TIME CARD.

Application filed October 21, 1919. Serial No. 332,279.

To all whom it may concern:

Be it known that I, EDWARD R. CROCKETT, a citizen of the United States, residing at New York, in the county of New York and State of New York, have invented certain new and useful Improvements in Time Cards; and I do hereby declare the following to a full, clear, and exact description of the invention, such as will enable others skilled in the art to which it appertains to make and use the same.

The objects of this invention are to provide a time card with means for readily ascertaining wage earnings; to provide the scale of hours and earnings from which such wages for any number of hours or fractional parts of hours may be computed; to not interfere with the use of the card with the time clocks now in use in any way; to avoid the necessity of complicated computations; to secure simplicity of construction and use; and to obtain other advantages and results as may be brought about in the following description.

Referring to the accompanying drawing in which like numerals of reference indicate similar parts throughout the several views,

The figure is a face view of a time card incorporating my invention.

In the specific embodiment of the invention illustrated in said drawing, reference numeral 1 indicates in general the time card which is substantially the same size and configuration as cards now in general use for this purpose. This card has upon its face the usual cross lines 2 and vertical lines 3, which block the card into spaces for receiving the time clock stamp as is usual in cards of this nature.

Arranged convenient to said spaces is a table or scale 4 of hours and earnings from which wages may be computed. Preferably this scale of hours is divided into two parts, namely, one part 5 wherein earnings for fractional parts of hours are indicated and another part 6, in which whole hours are indicated. Furthermore, this latter portion of the scale is arranged adjacent the time stamp space and the horizontal lines 2 are utilized for separating the several elements of the scale. The portion of the scale indicating the fractional parts of hours may be conveniently placed above the spaces for the time stamp as shown in the drawing. It is understood that the particular scale is to be varied according to the rate of pay, that is,

in any shop or office, each employee will have a card upon which the scale is made up to agree with his rate of pay. For instance, the card shown in the drawing is arranged to indicate the pay at a rate of 30¢ per hour. Preferably, the whole number of hours is made in even hundreds of hours, that is, 100, 200, 300, etc., so that it is only necessary to place a decimal point in the rate of pay according to the number of hours worked. In carrying out this feature above mentioned, the designation 100 is the smallest number of whole figures appearing, and directly under it is placed 03000, which indicates in dollars and cents (decimal point being omitted) the pay for 100 hours. For convenience in placing the decimal, it will be noted that the digits indicating the number of hours are directly above the digits of the wage earnings so that wherever the decimal is placed in the number representing hours, the decimal for the wages will be directly below it. Thus, if the pay is for one or ten hours, the decimal points are placed accordingly. Directly beneath the 100 hour rate, and preferably in a space divided off by suitable lines, is the designation for 200 hours and the corresponding rate, and beneath that 300, etc., up to 900.

Obviously, if the total time is any number of hours above 10 and below 20, it is only necessary to add earnings for the unit number of hours to the earnings for 10 hours, which will give the complete number; or if the number of hours lies between 20 and 30, it is only necessary to add earnings for the unit number of hours to the earnings for 20 hours, etc. In this way the wages for the week are very readily computed without pencil or paper and it is obvious to the wage earner in looking at his card whether or not the computation is correct.

While I have specifically illustrated my invention in connection with a time card and shown a specific rate, it is to be understood that I do not confine myself to such details but may employ other rates or cards. It is furthermore to be noted that the scale has been so placed upon the card as not to interfere with the use of the card with the time clocks in any way, thus adding to the desirability of the card.

As a specific example of use of the card, the same has been shown as having been used for one day, the time clock stamp showing

the times which the employee went to work and stopped for lunch and left at night. From this it is easily ascertained the number of hours which the employee worked for that day, as is usual, and in this particular instance amounted to $10\frac{1}{4}$ hours. Of course where the employee works for more than one day all of the total number of hours for the several days work will be added up and will constitute the "total time" for which a space is provided at the bottom of the card. In the particular example shown, where the total time amounts to $10\frac{1}{4}$ hours, the pay for the whole number of hours is obtained by mentally placing a period between the two cyphers of the 100 of the scale thus making it 10 to correspond with the whole number of hours. Then by mentally placing a decimal point directly below the decimal point placed in the 100 of the scale, gives the \$3.00 as the pay for 10 hours work. Added to this pay of \$3.00 for 10 hrs. is the cents indicated under the $\frac{1}{4}$ in the scale, thus totaling 3.075 as the

total pay for $10\frac{1}{4}$ hours. It is believed 25 obvious from this simple example, how the card is to be used and therefore a more extended or elaborate description is not believed necessary.

Having thus described my invention, I 30 claim:

1. A time card having thereon a scale showing earnings for fractional parts of hours and for even hundreds of hours whereby earnings for tens or units may be 35 determined by placing a decimal point accordingly.

2. A time card having thereon a scale showing hours and earnings one above the other with the digits of one number arranged with respect to digits of the other number so that the decimal points may be inserted in said numbers one below the other and thereby indicate the wages for the 40 number of hours so determined.

In testimony whereof I affix my signature.

EDWARD R. CROCKETT.
